Primary Examiner — Manpreet Matharu*Assistant Examiner* — Lisa A Grabenstetter(74) *Attorney, Agent, or Firm* — Avery N. Goldstein; Blue Filament Law PLLC(57) **CLAIM**

The ornamental design for a foot spa bowl, as shown and described.

DESCRIPTION

FIG. 1 is a top perspective view of a foot spa bowl showing my new design;

FIG. 2 is a bottom perspective view thereof;

FIG. 3 is a right side view thereof;

FIG. 4 is a left side view thereof;

FIG. 5 is a front view thereof;

FIG. 6 is a rear view thereof;

FIG. 7 is a top plan view thereof; and,

FIG. 8 is a bottom plan view thereof.

The broken line portions of FIGS. 1, 2, 7, and 8 are included to show unclaimed subject matter only and form no part of the claimed design.
